(57) **CLAIM**

The ornamental design for a folding scooter, as shown and described.

DESCRIPTION

The nature and intended use of the article in which the design is embodied is that of a human-powered, folding scooter for children and the like.

FIG. 1 is a side view of a folding scooter showing my new design;

FIG. 2 is a rear view thereof;

FIG. 3 is a front view thereof;

FIG. 4 is a top view thereof; and,

FIG. 5 is a bottom view thereof.

The portions of the footboard shown in broken lines form no part of the claimed design.
